UNITED STATES PATENT OFFICE.

THOMAS ELLIOTT, OF BIRMINGHAM, ALABAMA, ASSIGNOR TO THE CINCINNATI CAR CORPORATION, OF CINCINNATI, OHIO, A CORPORATION OF OHIO.

RAIL BRAKE FOR RAILWAY CARS.

Application filed August 5, 1926. Serial No. 127,453.

This invention relates to rail brakes for railway cars, more particularly the type known as electrically operated cars where an electric motor is employed.

5 This invention is kindred to that set forth in my Patent No. 1,645,741, Oct. 18, 1927, in so far as concerns the general feature of suspending the rail brake shoes a safe distance from the rails, then re-positioning 10 them to a point where they are within a magnetic field established between the shoes and the rails by magnetizing the shoes, and thence magnetically drawing and applying the shoes to and against the rails; but differs from said other invention in the means 15 and mode of closing the solenoid circuit utilized in positioning the shoes to a point within the magnetic field and closing the magnet brake circuit utilized to magnetize 20 the shoes.

In other words the present invention is directed to a pneumatic means of opening and closing said two circuits the solenoid and the magnet brake circuits.

25 In the accompanying drawings,

Figure 1 is a view, essentially diagrammatic, showing the pneumatic pipe lines and pneumatic motor utilized in operating the switch device for opening and closing the 30 solenoid and magnet brake circuits;

Fig. 1^a is an enlarged detailed view showing the double air valve and portions of the "straight" airline and emergency air line pipes and the pipe from the double valve to 35 the air cylinder;

Figure 2 is a side elevation, on an enlarged scale, of a truck and my improved rail brake mounted thereon, the normal position of the shoes being indicated in full lines, 40 the upper dotted lines indicating the magnetic field position and the lower dotted lines the rail contact or braking position;

Figure 3 is a detail view, partly in elevation and partly in section, of the magnetic housing and shoes with the supporting beam 45 and of the positioning solenoid and its lever devices with its attaching bracket;

Figure 4 is a plan view of the housing for the magnets for creating the magnetic field, 50 with part of the truck beam shown in section;

Figure 5 is a detail transverse sectional view of the magnet housing and the shoes, the section being taken on the line 5—5 of 55 Figure 6;

Figure 6 is a longitudinal vertical sectional view through the casing and contained magnets showing one of the shoes in side elevation.

In Figure 1, the numeral 1 designates the 60 motorman's air valve used for the quick admission of air from the supply pipe 2 to the usual cylinder of the air engine employed in applying the brakes, in which case the air under pressure passes from a storage tank 1^a 65 through the pipe 2, the valve 1 and either the emergency pipe line 3 or the "straight" air line 6 for ordinary braking. I utilize these standard features for operating the air engine or motor indicated at 4. This motor- 70 man's air valve also has the usual exhaust pipe 2^a. A branch pipe 7 passes from the emergency line 3 to the inlet pipe 8 of this engine or motor through a double valve 8^a and a branch pipe 9 passes from the ordinary air line 6 to this inlet pipe 8 through 75 this same valve 8^a, as seen in Figure 1.

It will be seen that the valve 8^a contains a ball 8^b adapted to travel back and forth in the passage 8^c, so as to be seated either on 80 the seat 8^d or 8^e, according to whether the air enters the casing 8^a through the "straight" airline 9 or the emergency airline 7. When the air enters through the "straight" airline it seats the ball 8^b in the seat 8^e which allows the air to pass from the casing 8^a into the pipe 8 and thence into the cylinder 4. But when the air enters the casing 8^a through the emergency line 7 it sends the ball against the seat 8^d and then enters the pipe 8. Thus 85 the ball moves from one seat to the other and allows the air to pass to the pipe 8 irrespective of whether the air is received from the "straight" airline or emergency airline 7.

Then when the piston in the cylinder 4 is 90 to be returned toward the left-hand end of cylinder viewed in Fig. 1, by the action of the spring 4^a, the air will pass or exhaust from the cylinder back into the valve casing 8^a and thence into the "straight" airline 9 100 if that airline is the line from which the air last entered the valve, the ball 8^b in that case being still seated on the seat 8^e. But if the last charge of air was from the emergency line 7, then the return of the piston would 105 discharge or exhaust the air from the cylinder through the valve to the pipe 7 because in that case the ball would then be seated on the seat 8^d.

And it will further be understood that if 110

the motorman has adjusted the valve 1 to admit air to the "straight" airline 6, 9, he would turn the valve 1 back to normal when he wished to discharge or exhaust air from the cylinder 4, such normal position putting the conventional exhaust pipe 2^a in communication with the line 6, 9.

And on the other hand if he had adjusted the valve 1 to supply air to the emergency line 3, 7, and later wanted to exhaust air from the cylinder he would return the valve 1 to normal position which would open communication between this same conventional exhaust pipe 2^a to the emergency line 3, 7.

15 The engine or motor 4 comprises a cylinder and a piston therein to which latter is connected a switch device 10 which is actuated thereby to close the solenoid circuit and then to close the magnet brake circuit 20 immediately after which the solenoid circuit is opened by the further movement of the switch device, while the magnet circuit remains closed until the then braking operation is completed, when the switch device 25 returns to normal position and leaves both circuits open, as will presently appear.

When such air is introduced into the cylinder behind the piston it advances the latter, whereby the switch device 10 is made to 30 contact first with the terminals *a* and *b* of the solenoid circuit 13, to close that circuit, and then to contact with the terminals *c* and *d* of the magnet brake circuit 14 to close that circuit.

35 With these operations the solenoid circuit is first closed to energize the solenoid generally indicated in Figure 1 at 15 to cause the core thereof to magnetically operate the devices hereinafter to be described which cause the brake shoes to be positioned within the magnetic field to be established between the shoes and the rails, so that the shoes will thereby be drawn to and against the rails to effect a braking action. Then the magnet 40 circuit 14 is closed to energize the magnets contained in the casing 16, to be hereinafter referred to, to magnetize the shoes when they are within magnetic distance from the rails so as to set up a magnetic field whereby the shoes will be drawn to and against the rails.

In order to return the switch device 10 to normal position when the shoes are to be released from the rails the air in the cylinder 4, and in the pipe lines 3 and 7, or 6 and 9, as the case may be, is exhausted by properly turning the handle of the valve 1 to permit of the escape of this air through the exhaust pipe 2^a, at which time piston-returning 55 spring 4^a acts on the piston and imparts to it a return movement to withdraw the switch-device 10 from the contacts *c*, *d*, and *a*, *b*, to demagnetize the shoe magnets and solenoid and allow the brake shoes to withdraw from the rails.

Referring now to Figures 2-6 of the drawings, in which is illustrated the mechanism by which the shoes are suspended at a safe distance away from the rails by which they are re-positioned to a place within the 70 magnetic field to be created between the shoes and the rails, and by which the shoes are to be magnetized to create a magnetic field as between themselves and the rails, so that they will be magnetically brought into 75 strong contact with the rails, attention is first directed to Figure 2 where a conventional or other form of railway truck is shown to whose side frame generally indicated at 20 I attach the brake mechanism. 80 The latter comprises a housing consisting of side plates 21 held together by bolts 22 which constitute the cores of the magnets 18. Between the plates 21 I place a casing in the nature of a band of metal shown at 23 and 85 within which I place the wire windings which with the cores 22 constitute the magnets which when energized by an electric current create the magnetic field by reason of the resulting magnetizing of the plates 21 and the shoes 24. These shoes are connected together by straps 25 secured to the shoes by bolts 26, and so may be readily renewed when worn out or if broken. These bolts pass through the projecting ends 27 of 90 the side plates 21 and down into the threaded openings in the shoes to receive them. The bolts thus connect together the shoes, the side plates, and the yokes, and render the 95 shoes removable when worn or broken. 100

In order to mount the housing, generally indicated at 19, slidably on the side frame 20 I provide one of the plates 21 with guides 28 which fit within the ways 29 in the side plates 20 as best shown in Figures 3 and 4. 105 This construction also puts the drag strains of the shoes on the side-frame of the truck.

110 Springs 30 are anchored at their lower ends, as shown at 31, to the connecting straps 25 and at their upper ends to plates 32 secured to the transoms 33, with adjusting and locking nuts 34 to adjust the tension of the springs and lock the fastening. One manner of connecting the springs 30 consists of short bolts 30^a secured at one end to the 115 upper end of the springs and other short bolts 30^b secured to the lower end of the springs. Any convenient manner of securing the springs to these bolts may be employed.

120 Thus it will be seen that the housing 19 constructed in the manner before described is suspended by the springs 30 so that the connected shoes 24 may be first held in their normal position as shown in full lines in 125 Figures 2 and 3; but may be depressed to their next position indicated by the dotted lines 24^a which brings them within the influence of the magnetic field created when the magnets 18 are energized; and from 130

which position indicated at 24^a they are magnetically drawn down against the top face of the rail as indicated at 24^b in Figures 2 and 3.

5 Referring again to Figure 6, it will be seen that the chamber within the general housing 19 is filled with a water-proof material, which in practice is poured into the chamber through an opening 19^a and which material effectually protects these magnets 18 from water and weather conditions generally. One of the terminals 20^a is grounded and the other 20^b runs to the trolley circuit.

10 I will now refer to the solenoid mechanism by which the shoes are moved against the tension of the springs 30 from their normal full line position shown in Figure 3 to their magnetic-field position shown at 24^a in that figure and whence they are snapped down 15 to the rails to the position shown in 24^b in said figure.

15 A hanger 35 is secured at its ends to the transoms 33 as by bolts and nuts 36, as best seen in Figure 2. On this hanger is mounted the solenoid 37 of conventional type, such as composed of a spool 38 on which is wound the wire 39 with a core 40 within the spool, seated upon a coil spring 41 whose function is to maintain the core in magnetic contact with the lever 42 so that when the solenoid is energized and the core is drawn magnetically to its natural position with respect to the coil, the core will magnetically draw the lever 42 downward and cause it 20 in turn to effect a downward movement of the lever 43 to depress the shoes 24 against the tension of the springs 30. A connection must be formed between the levers 42 and 43. Preferably this connection consists 25 of a bolt 44 whose head rests on the lever 43 through which the bolt passes and whence it passes through the lever 42. An adjusting nut 45 held by a lock nut 46 makes it possible to adjust the relation of the levers 30 42 and 43 so that the levers will be given the appropriate movement when the core of the solenoid is magnetically drawn downward taking with it the lever 42.

35 Thus it will be seen that mechanism is provided by which the shoes are suspended normally at a safe distance from the rails, so that they will not foul with the rails by season of any up and down motions of the truck due to the travelling of the wheels 40 over the rails; and yet that the shoes are capable instantly of being given a new position by the magnetic action of a solenoid, the new position being such that the shoes are within a magnetic field created by magnets associated with the shoe supports so as to magnetize these shoes; and from which latter position the shoes are magnetically carried to and maintained in forcible contact with the rails.

45 It will be understood that I desire to com-

prehend within my invention such modification as may be necessary to adapt it to varying conditions and uses.

Having thus fully described my invention, what I claim as new and desire to secure by Letters Patent, is:

5 1. In a rail brake, the combination with 70 brake shoes, mechanism to suspend the shoes normally a safe distance from the rails, a solenoid to position the shoes within magnetic range of the rails, and electrical mechanism consisting of magnets to magnetize the shoes, whence the shoes are attracted to and against the rails, of a pneumatic motor, a switch device for controlling said electrical mechanism operated thereby, an air valve and a pipe line from said valve to said pneumatic motor.

10 2. In a rail brake, the combination with 75 brake shoes, mechanism to suspend the shoes normally a safe distance from the rails, a solenoid to position the shoes within magnetic range of the rails, and electrical mechanism consisting of magnets to magnetize the shoes, whence the shoes are attracted to and against the rails, of a pneumatic motor comprising a cylinder and piston, a switch device for controlling said electrical mechanism operated by said piston, and air valve and a pipe line from said 80 valve to said pneumatic cylinder.

15 3. In a rail brake, the combination with 85 brake shoes, mechanism to suspend the shoes normally a safe distance from the rails, a solenoid to position the shoes within 90 magnetic range of the rails, and electrical mechanism consisting of magnets to magnetize the shoes, whence the shoes are attracted to and against the rails, of a pneumatic motor, a switch device actuated thereby to open and close the circuits of said 95 solenoid and magnets, a manually controlled air valve, emergency and ordinary air lines extending from said valve to said pneumatic motor, whereby the latter may 100 be operated to actuate the switch device either when ordinary or emergency braking is desired.

20 4. In a rail brake, the combination with 105 brake shoes, mechanism to suspend the shoes normally a safe distance from the rails, a solenoid to position the shoes within magnetic range of the rails, electrical mechanism consisting of magnets to magnetize the 110 shoes, whence the shoes are attracted to and against the rails, a solenoid circuit normally open and a magnet circuit also normally open, of a switch device adapted to close the solenoid circuit and then to close the magnet circuit, a pneumatic motor which 115 so actuates said switch device, a manually operable air valve and an air line from said valve to said motor to admit air under pressure to actuate the motor.

25 5. In a rail brake, the combination with 120

brake shoes, mechanism to suspend the shoes normally a safe distance from the rails, a solenoid to position the shoes within magnetic range of the rails, and electrical mechanism consisting of magnets to magnetize the shoes, whence the shoes are attracted to and against the rails, of a pneumatic motor, a switch device for controlling said electrical mechanism operated thereby, an air valve, a pipe line from said valve to said pneumatic motor, and an exhaust device for said valve to permit the return movement of the switch device.

6. In a rail brake, the combination with
15 brake shoes, mechanism to suspend the shoes normally a safe distance from the rails, a solenoid to position the shoes within magnetic range of the rails, electrical

mechanism consisting of magnets to magnetize the shoes, whence the shoes are attracted to and against the rails, a solenoid circuit normally open and a magnet circuit also normally open, of a switch device adapted to close the solenoid circuit and then to close the magnet circuit and open 25 the solenoid circuit, a pneumatic motor which so actuates said switch device, a manually operable air valve, an air line from said valve to said motor to admit air under pressure to actuate the motor, and exhaust 30 devices to permit the return movement of the switch device to open said circuits.

In testimony whereof, I affix my signature.

THOMAS ELLIOTT.
